UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

Specification forming part of Design No. 11,147, dated April 8, 1879; application filed December 2, 1878.
[Term of patent 3½ years.]

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

It consists of what is known as "chintz work" of leaves and flowers, too minute to admit of a precise description, arranged on a ground that contrasts strongly with the colors of the "chintz-work."

I claim—

The design for a carpet, consisting of the chintz-work of leaves and flowers on a ground contrasting with the colors of the chintz-work, as shown in the accompanying photographic illustration.

In testimony whereof I have signed my name to this specification, in the presence of two subscribing witnesses, this 25th day of November, 1878.

THOMAS J. STEARNS.
